UNITED STATES PATENT OFFICE.

OBED W. BARNARD, OF SENECA, KANSAS.

DESIGN FOR A WASHING-MACHINE DASHER.

SPECIFICATION forming part of Design No. 19,856, dated May 27, 1890.

Application filed March 25, 1890. Serial No. 345,274. Term of patent 7 years.

To all whom it may concern:

Be it known that I, OBED W. BARNARD, a citizen of the United States, residing at Seneca, in the county of Nemaha and State of Kansas, 5 have invented a new and useful Design for a Washing-Machine Dasher, of which the following is a specification.

The invention relates to a new and improved design for washing-machine dashers.

10 The single figure of the drawing is a side elevation of the washing-machine dasher, showing my design.

15 The leading feature of my design consists in a U-shaped dasher having a series of horizontally-curved cross-pieces representing spirals, as shown.

20 A designates the frame of the dasher, of an approximately U shape, having its ends extended at right angles to the sides of the frame provided with the reduced annular portions a.

B designates a series of cross-pieces which extend horizontally from side to side of the rectangular frame, representing spirals and forming the main body of the dasher.

25 What I claim is—

The design for washing-machine dashers herein shown and described, the same comprising the U-shaped frame and the series of curved horizontal cross-pieces representing spirals, substantially as described.

30 In testimony that I claim the foregoing as my own I have hereto affixed my signature in presence of two witnesses.

OBED W. BARNARD.
